UNITED STATES PATENT OFFICE.

JOSEPH COPLINKY, OF HARRISBURG, PENNSYLVANIA.

CAN-OPENER.

No. 926,051.

Specification of Letters Patent. Patented June 22, 1909.

Application filed March 20, 1909. Serial No. 484,615.

To all whom it may concern:

Be it known that I, JOSEPH COPLINKY, a citizen of the United States, residing at Harrisburg, in the county of Dauphin and State of Pennsylvania, have invented new and useful Improvements in Can-Openers, of which the following is a specification.

This invention has for its object to provide a novel form of implement for opening cans or like sheet metal packages containing goods of different kinds, said implement being of such formation as to adapt itself to cans or packages of varying sizes and shapes whether circular, oval or rectangular. 10
15 The primary purpose of the invention is the provision of a tool or implement of the character aforesaid comprising pivoted members formed of telescoping sections, one of said members being provided with a cutter and the other member having a centering point or points to fix the relative position of the stationary member when the implement is in operation.

A further purpose of the invention is to supply an implement for the purposes herein outlined which may be cheaply and economically manufactured and comprising parts adapted to be readily assembled and easily and cheaply replaced in the event of 20 any one of the parts becoming disabled so as to render the implement unfit for further effective service without being repaired.

In the drawings herewith a preferred embodiment of the invention is illustrated, 35 however, it is to be understood that within the scope of the invention as claimed, various changes, in the form, proportion and minor details may be resorted to without departing from the spirit of the invention.

40 Referring to the accompanying drawings forming a part of the specification, Figure 1 is a top plan view of a can opener embodying the invention, parts being broken away. Fig. 2 is a view similar to Fig. 1 as it appears from the reverse side. Fig. 3 is a transverse section on the line 3—3 of Fig. 2 looking toward the pivot pins of the members. Fig. 4 is a detail perspective view of a portion of the handle or relatively station- 45 50 ary member, the outer portion being broken

away. Fig. 5 is a perspective view of the cutter member, the handle portion being broken away. Fig. 6 is a perspective view of the intermediate section of the cutter member. Fig. 7 is a transverse section on the line 7—7 of Fig. 2. 55

Corresponding and like parts are referred to in the following description and indicated in all the views of the drawings by the same reference characters. 60

The two members are designated by the reference letters A and B and are pivotally connected at one end by a pivot fastening 1 of any construction. Each member comprises a plurality of sections which are telescopically or slidably related to admit of the lengthening or shortening of the members. 65

The member A is relatively stationary when the implement is in use and may be properly designated as the handle member and it is provided with one or more spurs or points 2. The inner section 3 of the handle member is provided at one end with a disk or hub 4 which is centrally apertured to receive the pivot fastening 1. The opposite end portion of the section 3 is recessed in one side as indicated at 5 to receive the cooperating section 6 which is slidably mounted therein. Longitudinal grooves 7 are formed in the walls bordering upon the recess 5 and receive lugs 8 projected laterally in opposite directions from the inner end of the section 6. Grooves 9 communicate at their inner ends with the longitudinal grooves 7 and extend outward through the recessed side of the section 3 and provide passages for reception of the lugs 8 when assembling the sections 3 and 6. The outer ends of the longitudinal grooves 7 are closed thereby preventing outward displacement of the section 6 and limiting the outward movement thereof as indicated most clearly in Figs. 1 and 2. Each of the sections 3 and 6 is provided with a point or spur 2 which is adapted to penetrate the can or package when placing the implement in position preliminary to operating the same to effect an opening of the can. The section 6 has a longitudinal slot 10 through 90 95 100

which a thumb screw 11 or like fastening passes and which is threaded into the outer end of the section 3. The fastening 11 provides ready and convenient means for securing the sections 3 and 6 in an adjusted position.

The cutter member B comprises a series of sections 12, 13 and 14 having a telescoping arrangement to admit of the member automatically lengthening or shortening so that the cutter 15 may follow an irregularly shaped can or package when opening the same. The inner section 12 is similar in construction to the section 3 and is provided 10 at one end with a disk or hub 16 having a central opening to receive the pivot fastening 1, said section having a recess 17 in one side to receive the section 13 and having longitudinal grooves 18 in the inner walls 15 thereof bordering upon the recess 17, said grooves being closed at their outer ends and communicating at their inner ends with lateral grooves 19 which open through the recessed side of the section 12 and provide 20 passages for the lugs 20 projected laterally from the inner end of the section 13. The section 13 has a recess 21 in one side extending throughout the length thereof and adapted to receive the section 14. Longitudinal grooves 22 are formed in the walls of 25 the section 13 bordering upon the recess 21 and receive lugs 23 projected laterally from the inner end of the section 14. The grooves 22 are closed at their outer ends in a manner 30 similar to the longitudinal grooves 7 and 18 to engage with the lugs 23 and limit the outward movement of the section 14. The section 14 is adapted to be placed within the recess 21 of the section 13 with the lugs 23 35 clearing the inner end of said section 13 after which the section 14 is moved outward to cause the lugs 23 to enter the grooves 22.

The cutter 15 may be of any construction 40 and is fitted to the section 14 in such a manner as to admit of its replacement when broken or otherwise rendered unserviceable. A grip or handle piece 24 is fitted to the outer end of the section 14 and a similar grip or handle piece 25 is fitted to the outer 45 end of the section 6.

When the component parts of the implement are assembled the tool presents the appearance substantially as illustrated in Figs. 1 and 2. When it is required to open a can 50 or sheet metal package, one or both of the points 2 are forced into the cover or part of the can to be opened thereby fixing the position of the handle member A. The cutter 15 of the operating member B is forced 55 through the cover of the can preferably near the outer edge thereof after which, the handle piece 24 of the cutter member B is gripped and moved so as to cause the cutter 60 15 to follow the cover close to the edge or side of the can, the telescoping construction

of the cutter member admitting of the cutter 15 following the irregular shape of the cover and always remaining near to and following the side of the can whether the latter be round, square, oblong or of other form.

Having thus described the invention, what is claimed is—

1. A can opener comprising pivotally connected members, one of said members being extensible and comprising telescoping sections, a centering point applied to one of said members, and a cutter carried by the other member at the handle end. 75

2. A can opener comprising pivotally connected members, both members being extensible and each comprising telescopically related sections, a centering point applied to one of said members, and a cutter carried by the other member at the handle end. 80

3. A can opener comprising a handle member, an operating member pivotally connected to the handle member and comprising a series of telescoping sections, and a cutter fitted to the outermost telescoping section. 85

4. A can opener comprising pivotally connected members, one of said members adapted to be lengthened or shortened and comprising a series of telescoping sections, means for limiting the outward movement of the sections, and operating elements as a centering point and a cutter applied to the respective members, the extensible member having the operating element applied to its outermost section. 90

5. A can opener comprising members pivotally connected at one end, and each provided at its opposite end with a handle piece, and each of the members being formed of a plurality of telescoping sections provided 105 with means to limit their outward movement, one member having a spur upon the outermost section, and the other member having its outer section provided with a cutter. 100

6. A can opener comprising pivotally connected members, the one provided with a spur and the other having a cutter, and the member having the spur being linearly adjustable and comprising telescoping sections, and means for securing said sections in an 115 adjusted position. 110

7. A can opener comprising two extensible members each comprising telescoping sections, one member having a spur and the other member provided with a cutter at the handle end, and each member having a terminal section comprising a recessed portion to receive the adjacent section and a flattened disk or hub portion centrally apertured, said disks overlapping, and a pivot 120 fastening passed through the openings of said disks and connecting the members. 125

8. A can opener comprising pivotally connected members, the one provided with a spur and the other with a cutter, and each 130

of said members comprising telescoping sections, one of the sections having a recess in a side and longitudinal grooves in the walls of the recess, said grooves being closed at their outer ends and having lateral grooves in communication with their inner ends, and the adjacent section being provided with outwardly extended lugs to operate in the

longitudinal grooves of the first mentioned or mating section.

In testimony whereof I affix my signature in presence of two witnesses.

JOSEPH COPLINKY.
